PAPER BOX

Sterling R. Arner, Charlotte, N. C., assignor to Old
Dominion Box Company, Lynchburg, Va., a cor-
poration of Virginia

Application July 19, 1943, Serial No. 495,288

2 Claims. (Cl. 229—5.5)

This invention relates to a paper container and more especially to a cylindrical container such as used for packing half-pound and one pound quantities of tobacco, although it is to be clearly understood that this type of container can be used for any other purpose.

It is an object of this invention to provide a container having a hermetically sealed reinforced bottom, and one which presents a very neat appearance.

It is another object of this invention to provide a container having inner and outer side walls and having a bottom member whose edges fit snugly against the inner side walls of the container and a supplemental covering which holds the bottom in position, said supplemental covering extending over the lower edges of the inner shell of the container and being turned upwardly and embedded between the inner and outer shells of the container.

It is another object of the invention to provide a container having inner and outer sidewalls and having the outer sidewall extending farther downwardly than the inner sidewall and having a second bottom member whose periphery fits against the inner surface of the outer sidewall.

Some of the objects of the invention having been stated, other objects will appear as the description proceeds when taken in connection with the accompanying drawing, in which—

Figure 1 is an elevation with the lower portion thereof broken away, showing the container;

Figure 2 is an enlarged detail vertical sectional view of the lower portion of Figure 1.

Referring more specifically to the drawing, the numeral 10 indicates the inside side wall of the box which projects above the outer side wall 11, and a suitable cover is adapted to fit over the upper portion of the inside side wall 10, and have its lower edge fit snugly against the upper edge of the outside wall 11. The outside side wall 11 is covered with a suitable wrapper 12 on which trade-mark or other suitable printed matter is placed. The top edge of the wrapper 12 is turned inwardly and downwardly between the inner sidewall 10 and outer sidewall 11. Fitting snugly within the inner sidewall 10 is a bottom member 14 which is secured in position by means of a bottom label 15 which has its edges turned upwardly and secured by any suitable means such as an adhesive between the inner and outer sidewalls as at 16. This bottom retaining label 15 is usually composed of what is known as white face craft paper so as to give the proper strength for retaining the bottom 14 in position.

Disposed below label member 15 is an extra

bottom 20 which fits flush against the surface of label 15 and has its periphery fitting flush against the inner surface of the downwardly extending portion of the outer sidewall 11. The outer wrapper 12 is lapped over the peripheral portions of the additional bottom member 20 as at 21. Then an additional label 22 similar to label 15 is pasted over the extra bottom 20 and covers also the turned in portion 21 of the outer wrapper 12 as is clearly shown in Figures 1 and 2. This type of structure provides a very rigid and hermetically sealed bottom for a box.

In the drawing and specification, there has been set forth a preferred embodiment of the invention, and although specific terms are employed, they are used in a generic and descriptive sense only, and not for purposes of limitation, the scope of the invention being defined in the claims.

20 I claim:

1. A container having inner and outer side walls, a bottom having its periphery fitting snugly against the lower inner side wall, a label covering the lower surface of the bottom member and having its edges folded up between the inner and outer side walls, the outer side wall extending further downwardly than the inner side wall, an additional bottom member having its periphery fitting snugly against the interior surface of the outer side wall, and having one side fitting against the label on the first-mentioned bottom, the outer side wall having a covering whose upper edge is turned down between the inner and outer side walls, and whose lower edge is turned inwardly over the end of the outer side wall and against the lower surface of the second bottom member and a label adhesively secured to the lower surface of the second bottom member and to the inturned portions of the cover.

2. A container having inner and outer side walls, a bottom having its periphery fitting snugly against the lower inner side wall, a label covering the lower surface of the bottom member and having its edges folded up between the inner and outer side walls, the outer side wall extending further downwardly than the inner side wall, an additional bottom member having its periphery fitting snugly against the interior surface of the outer side wall, and having one side fitting against the label on the first-mentioned bottom, the outer side wall having a covering whose upper edge is turned down between the inner and outer side walls, and whose lower edge is turned inwardly over the end of the outer side wall and against the lower surface of the second bottom member.

STERLING R. ARNER.
